UNITED STATES PATENT OFFICE

160,603

CHAIR OR SIMILAR ARTICLE

Preston Reed Hubbell, Fort Lauderdale, Fla.

Application September 3, 1948, Serial No. 148,449

Term of patent 14 years

(Cl. D15—1)

To all whom it may concern:

Be it known that I, Preston Reed Hubbell, a citizen of the United States of America, residing at Fort Lauderdale, in the county of Broward, in the State of Florida, have invented a new, original, and ornamental Design for a Chair or Similar Article, of which the following is a specification, reference being had to the accompanying drawing, forming a part thereof.

I claim:

The ornamental design for a chair or similar article, substantially as shown.

PRESTON REED HUBBELL.
